UNITED STATES PATENT OFFICE.

THOMAS F. WILLIAMS, OF CHICAGO, ILLINOIS.

ACETYLENE-GAS GENERATOR.

SPECIFICATION forming part of Letters Patent No. 619,814, dated February 21, 1899.

Application filed July 16, 1898. Serial No. 686,096. (No model.)

To all whom it may concern:

Be it known that I, THOMAS F. WILLIAMS, a citizen of the United States, residing at Chicago, in the county of Cook and State of Illinois, have invented certain new and useful Improvements in Valves for Lamps, &c., of which the following is a specification, reference being had to the accompanying drawing.

My invention relates to valves designed for use in acetylene-gas lamps and in other situations where a slow and uniform discharge of liquid from a reservoir or other suitable source is desired; and it has for its object to provide a valve which will be especially adapted for use in acetylene-gas lamps, although not limited to such use alone.

In acetylene-lamps it has usually been the practice to provide a suitable receptacle for the calcium carbid and a reservoir for the water, which is supplied slowly and continuously while the lamp is operating to the carbid. In lamps of this character, especially in small sizes commonly used for bicycles, the supply of water necessary to generate sufficient gas to maintain the desired light is necessarily small, the water usually being permitted to drop slowly into the carbid-receptacle. To accomplish this, a very fine outlet has been employed, with the result that from the sediment carried in the water and other causes the passage is soon clogged and the supply of water cut off.

The object of my invention is to avoid the objection above mentioned; and it consists in providing valve mechanism of improved construction in which means is provided for readily clearing the discharge-passage and maintaining a constant uniform supply of water to the carbid-receptacle. I accomplish this object as hereinafter specified and as illustrated in the drawing.

That which I regard as new will be set forth in the claims.

Referring to the accompanying drawing, in which the figure is a side elevation of a bicycle-lamp, the water and carbid receptacles, with the valve mechanism, being in section, 1 indicates the lamp, 2 the outer casing of the carbid-receptacle 3, and 4 the water-receptacle, which, as shown, is located above the carbid-receptacle back of the lamp.

5 indicates a valve-tube which in the con-

struction herein shown extends vertically through the water-reservoir and projects into the carbid-receptacle, having an outlet or nozzle 6. The valve-tube 5 communicates with the interior of the water-reservoir by means of a tube 7, which is provided with a valve 8, by which it may be opened and closed. In the construction shown the valve 8 extends upward through the top of the water-reservoir, so that it may be readily operated. The outlet of the valve-tube 5 is almost completely closed by the lower end of a rod 9, which is arranged in the tube 5 and extends through the upper end thereof, as illustrated in the drawing. The lower end of the rod 9 is slightly less in diameter than the internal diameter of the outlet 6, so that water is permitted to pass slowly through such outlet and drop into the carbid-receptacle at the proper rate. As hereinbefore stated, however, after the lamp has operated for a time, the outlet-passage becomes clogged, so as to interfere with the passage of the water. To clear the discharge-passage, the rod 9 is made movable longitudinally of the discharge-passage, so that the fine particles of solid matter which clog the passage may be broken loose and the passage of water restored. The movement of the rod 9 is effected simply by downward pressure, the rod being restored to its normal or upper position by a spring 10, which bears against a collar 11, carried by the rod 9, and against an internal annular flange 12, arranged in the valve-tube 5.

When the outlet-passage from the valve-tube 5 has become clogged, so as to interfere with the proper generation of gas to such an extent as to make it noticeable, it is desirable that an extraordinary amount of water may be supplied at once, so that gas may be generated rapidly until the normal condition of things has been restored, and to this end means is provided for temporarily enlarging the water-passage when the rod 9 is moved to clear the passage, such means in the construction herein shown consisting of a depression or recess 13 in the rod 9, near the lower end thereof, by which the area in cross-section of the rod at that point is reduced, affording a larger channel for the passage of the water when the rod is depressed. When, however, the rod 9 returns to its normal po-

sition, the depressed portion of the rod lies above the discharge-passage, so that the ordinary feed is maintained.

It will be understood that various modifications of my improvements may be made, and I therefore do not restrict myself to the specific details of the construction shown and described. Neither do I limit my improvements to use with acetylene-lamps, as they may be employed in any other situation to which they are adapted.

That which I claim as my invention, and desire to secure by Letters Patent, is—

1. In a lamp, the combination with a liquid-reservoir, of a valve-tube having an outlet-passage for the discharge of liquid therefrom, an inlet from said reservoir to said tube, a valve controlling said inlet, a rod in and almost entirely closing the outlet of said valve-tube, said rod being movable longitudinally, and a spring for returning said rod to its normal position, substantially as described.

2. In a lamp, the combination with a liquid-

reservoir, of a valve-tube having an outlet-passage for the discharge of liquid therefrom, 25 an inlet from said reservoir to said tube, a valve controlling said inlet, and a rod in and almost entirely closing the outlet of said tube, said rod being movable longitudinally and having a depression or recess movable into 30 the outlet-passage and so constructed that the water drips from the end of the rod, substantially as described.

3. In a lamp, a holder for calcium carbid or similar material, an outer casing from which 35 the carbid-holder is separable, a water-holding vessel at a higher elevation, a tube leading from the casing and rising higher than the water-level, and a movable rod therein for freeing the tube from obstruction, and a 40 valve to admit water into the tube, substantially as specified.

THOMAS F. WILLIAMS.
